US00D806223S

(12) **United States Design Patent** (10) Patent No.: **US D806,223 S**
Allard et al. (45) Date of Patent: **** Dec. 26, 2017**

(54) **FAN**

(71) Applicant: **Dometic Sweden AB**, Solna (SE)

(72) Inventors: **James Allard**, Davisburg, MI (US); **Mark L. Smith**, Buchanan, MI (US); **Hari Sunkara**, Elkhart, IN (US)

(73) Assignee: **Dometic Sweden AB**, Solna (SE)

(**) Term: **15 Years**

(21) Appl. No.: **29/588,249**

(22) Filed: **Dec. 19, 2016**

Related U.S. Application Data

(62) Division of application No. 29/532,130, filed on Jul. 1, 2015, now Pat. No. Des. 787,037.

CLAIM

The ornamental design for a fan, as shown and described.

DESCRIPTION

FIG. 1 is a front perspective view of the design of a first embodiment of the fan;

FIG. 2 is a front elevation view of the design of FIG. 1;
FIG. 3 is a rear elevation view of the design of FIG. 1;
FIG. 4 is a first side elevation view of the design of FIG. 1, with the second side elevation view of the design being a mirror image of FIG. 4;

FIG. 5 is a top plan view of the design of FIG. 1, with the bottom plan view of the design being a mirror image of FIG. 5;

FIG. 6 is a cross-sectional plan view of the design of FIG. 1 taken along the line 6-6 in FIG. 2;

FIG. 7 is a rear perspective view of the design of FIG. 1;
FIG. 8 is a front perspective view of the design of a second embodiment of the fan;

FIG. 9 is a front elevation view of the design of FIG. 8;
FIG. 10 is a rear elevation view of the design of FIG. 8;
FIG. 11 is a first side elevation view of the design of FIG. 8, with the second side elevation view of the design being a mirror image of FIG. 11;

FIG. 12 is a top plan view of the design of FIG. 8, with the bottom plan view of the design being a mirror image of FIG. 12;

FIG. 13 is a cross-sectional plan view of the design of FIG. 8 taken along the line 13-13 in FIG. 9;

FIG. 14 is a rear perspective view of the design of FIG. 8;
FIG. 15 is a front perspective view of the design of a third embodiment of the fan;

FIG. 16 is a front elevation view of the design of FIG. 15;
FIG. 17 is a rear elevation view of the design of FIG. 15;
FIG. 18 is a first side elevation view of the design of FIG. 15, with the second side elevation view of the design being a mirror image of FIG. 18;

FIG. 19 is a top plan view of the design of FIG. 15, with the bottom plan view of the design being a mirror image of FIG. 19;

FIG. 20 is a cross-sectional plan view of the design of FIG. 15 taken along the line 20-20 in FIG. 16; and,

FIG. 21 is a rear perspective view of the design of FIG. 15. The broken lines illustrating portions of the fan form no part of the claimed design.
